UNITED STATES PATENT OFFICE.

WILLIAM BROOKS, OF DANVILLE, ILLINOIS.

SPOTLIGHT.

Application filed December 17, 1924. Serial No. 756,513.

This invention relates to improvements in spotlights, for use upon motor vehicles, and has for its primary object to provide a means for moving the spotlight to various positions.

One of the important objects of the present invention is to provide a spotlight wherein the same is adapted to be controlled in its various adjusted positions at a point remote therefrom, the spotlight being adapted to be secured on the front of a motor vehicle, the operating means therefor being disposed within easy access of the operator of the motor vehicle.

A further object of the invention is to provide a spotlight of the above mentioned character, which may be readily and easily secured in position upon a motor vehicle the same being further simple in construction, inexpensive, strong and durable, and further well adapted for the purposes for which it is designated.

Other objects and advantages of this invention will become apparent during the course of the following description.

In the accompanying drawings, forming a part of this specification; and in which like numerals designate like parts throughout the same:

30 Figure 1 is a side elevation of the device embodying my invention.

Figure 2 is an enlarged detail of the upper portion of the drum, showing the manner in which the spotlight is mounted thereon.

35 Figure 3 is a fragmentary sectional view of the lower portion of the drum, illustrating the means for rotating the same.

Figure 4 is a detail of the plunger and the casing, in which the same is adapted for 40 slidable movement.

Figure 5 is a detail of the handle for rotating the flexible drive shaft.

Figure 6 is a front elevation of the handle, and

45 Figure 7 is a top plan view of the foot treadle.

In the drawings, wherein for the purpose of illustration is shown the preferred embodiment of my invention, the numeral 1 designates a supporting bracket, which is arranged on the front of a motor vehicle, in any suitable manner. Associated with the bracket and extending upwardly therefrom is the tubular shaft 2. Rotatably supported on the shaft 2 is the vertical drum 3. Suitable ball bearings, such as are shown at 4,

are associated with the shaft 2, for cooperation with the upper and lower ends of the drum respectively.

An arm 5 extends upwardly and outwardly from the upper end of the drum 3 and pivotally supported thereon, as at 6, is the spotlight supporting member 7, the spotlight being indicated at 8. As the latter may be of any well known construction, a further detailed description thereof is not thought necessary. A longitudinally slotted arm 9 extends rearwardly from the spotlight, and the purpose thereof will be herein-after more fully described.

70 Gear teeth, such as are shown at 11, are formed on the lower portion of the drum 3 and extend circumferentially therearound. A bracket designated generally by the numeral 12 is associated with the lower portion 75 of the tubular shaft 2 and provides a means for supporting the vertical stub shaft 13. A pinion 14 is keyed on the upper end of the vertical stub shaft 13 and meshes with the gear teeth 11, on the lower portion of the 80 drum 3. A bevelled gear 15 is carried by the lower end of the vertical stub shaft 13. A flexible drive shaft 16 extends longitudinally through the housing 17, and through a suitable bearing 18, at its forward end, 85 the bearing being supported on the bracket 1, as more clearly illustrated in Figure 3. A bevelled gear 19, is secured on the forward end of the flexible drive shaft 16 and meshes with the aforementioned bevelled 90 gear 15.

The rear end of the housing 17 is secured to a suitable bearing 20, which is supported, in a suitable opening provided therefor, in the instrument board A of a motor vehicle. 95 An axle 21 is journaled in the bearing 20, the forward end thereof being connected to the rear end of the flexible drive shaft 16. A handle 22 is associated with the opposite end of the axle, and provides a means where- 100 by the flexible shaft 15 will be rotated, causing the rotation of the drum 3, through the gearing above described, and simultaneously moving the spotlight in a horizontal plane, so that the rays of light therefrom may be 105 directed to either side of the road.

The spotlight is further adapted for tilting movement, and to this end a flexible rod or worm 23 is provided, the same having its forward portion extending upwardly 110 through the tubular shaft 2, and being secured at its upper end to the slotted arm 9,

which extends rearwardly from the spotlight 8, in the manner as indicated at 24. The opposite end of the cable 23 is secured to the forward end of a plunger 25, as at 26. A plunger 25 is adapted for slideable movement within a casing 27, the latter being pivotally supported, as at 28, on a suitable bracket 29, secured on the motor vehicle foot board. A housing for the cable is illustrated at 30, and the same is secured at one end to the forward end of the casing 27 and at its opposite end to the lower end of the tubular shaft 2.

The rear end of the plunger 25 extends outwardly from the rear end of the casing 27, and is secured to the upper end of the lever 31, as at 32. The lever 31 is associated at its lower end with the transversely extending shaft 33, the same extending through the upstanding ears 34 formed on the plate 35, the latter being secured to the foot board of the motor vehicle. A treadle 36 is associated with the shaft 32, and it is obvious that when the treadle has its forward portion depressed, by the foot of the operator of the motor vehicle, the plunger 25 will move forwardly within the casing 27, causing the forward end of the cable 23 to move upwardly within the tubular shaft 2, which extends through the drum 3, and thereby tilting the headlight 8 downwardly through the medium of the connection 24 with the slotted arm 9 of the headlight. Manifestly, by moving the pedal 36 in the opposite direction, the headlight 8 and its supporting arm 7 will swing upwardly on its pivot 6. A set screw or the like, shown at 37, cooperates with the casing and the plunger, for holding the latter in various adjusted positions, so that the headlight 8 may be prevented from accidental displacement from the position to which it has been tilted.

It will thus be seen from the foregoing description, that a spotlight has been pro-

vided, for use upon motor vehicles, which is of such construction as to enable the same to be rotated and tilted independently in a simple and efficient manner, the operating means therefor being disposed within easy access of the operator. Furthermore, the provision of a spotlight of the above mentioned character, enables the same to be readily secured in position upon a motor vehicle, without necessitating any material alterations of the parts of the motor vehicle, with which the same is associated.

While I have shown the preferred embodiment of my invention, it is to be understood that various changes in the size, shape and arrangement of parts may be resorted to, without departing from the spirit of the invention, and the scope of the appended claim.

Having thus described my invention, what is claimed is:

A device of the class described comprising a supporting bracket, a vertical shaft extending upwardly from said bracket, a drum adapted for rotation around said shaft, a spotlight mounted on the upper portion of said drum, a gear on the lower end of the drum, an arm extending laterally from the lower end of the shaft below said drum, a vertically disposed bearing bracket carried on the outer end of said arm, a stub shaft journaled for rotation in said bearing bracket, a pinion on the upper end of said stub shaft meshing with said gear, a beveled gear on the lower end of the stub shaft, a drive shaft, a beveled gear on the forward end thereof adapted for engagement with the aforementioned bevel gear, and actuating means associated with the opposite end of the drive shaft for rotating the drum and the spotlight.

In testimony whereof I affix my signature.

WILLIAM BROOKS.
